FULLING AND WASHING MACHINE

David Gessner, Worcester, Mass.

Application September 19, 1934, Serial No. 744,713

16 Claims. (Cl. 26—20)

This invention relates to machines for fulling and washing cloth preparatory to finishing operations thereon, this application being a continuation in part of my prior application on 5 Fulling machine, Serial No. 569,577, filed by me October 19, 1931 and patented October 16, 1934, Patent No. 1,977,579.

One object of my present invention is to provide an improved and simplified construction 10 of the fulling stocks and the supporting and actuating mechanism therefor.

A further object is to provide improved means for applying heat to the cloth during the fulling and washing operation thereon, preferably by 15 heating the conveyor belt on one or both sides thereof.

My invention further relates to arrangements 20 and combinations of parts which will be hereinafter described and more particularly pointed out in the appended claims.

A preferred form of the invention is shown in the drawings, in which

Fig. 1 is a side elevation of a fulling machine embodying my improvements;

Fig. 2 is an enlarged side elevation, partly in section, of certain portions of my improved machine;

Fig. 3 is a partial end elevation, partly in section, and looking in the direction of the arrow 30 3 in Fig. 2;

Fig. 4 is a detail plan view, looking in the direction of the arrow 4 in Fig. 3;

Fig. 5 is an end view of a modified construction 35 of fulling stock;

Fig. 6 is a detail side elevation, looking in the direction of the arrow 6 in Fig. 5, and

Fig. 7 is a detail sectional view, taken along the line 7—7 in Fig. 1.

Referring to the drawings, my improved fulling 40 machine comprises a frame 10 having outwardly projecting end portions 11 and 12. A tank or trough 13 is mounted on the end portion 11 of the frame and a pair of driven squeeze rolls 14 are mounted above the tank 13.

The tank is supplied with a solution of soap 45 and water, or with any other desired solution, and the cloth C is drawn through the solution by the rolls 14 and thereafter passes around guide rolls 15 and is delivered to pleaters 16 by 50 which it is deposited in folded condition on a conveyor 20.

This conveyor 20 is preferably formed of a plurality of relatively narrow belts 20a, as shown in Fig. 3, which belts are driven by a drum 22 55 (Fig. 1) at the delivery end of the machine. The

drum 22 may be rotated by a belt 23 or in any other suitable manner.

The conveyor 20 also passes around guide rolls 24, 25, 26 and 27 and passes over fulling tables 30 and 31. A hand wheel 32 (Fig. 1) is provided 5 for adjusting the guide roll 27 to regulate the tension on the conveyor 20. Fulling stocks 33 (Fig. 2) are supported on bars 35 which are mounted at the lower ends of forked members 37 which have their upper ends pivoted on crank 10 portions 38 (Figs. 3 and 4) formed at the opposite ends of crank-shafts 40. Each crankshaft 40 is provided with a gear 41 (Fig. 2), which in turn is connected through an intermediate gear 42 to a pinion 43 on a drive shaft 44. 15

The drive shaft 44 is shown in Fig. 1 as provided with a large pulley or sprocket 45 connected by a belt or chain 46 to a driving motor M. Any other suitable means may be provided for 20 rotating the drive shaft 44. The shafts 40 and 25 crank portions 38 are so disposed that one set of fulling blocks rises as the other set descends.

After the fulling operation, the cloth C is drawn upward from the conveyor 20 over guide 30 rolls 48 and 49 (Fig. 1) and is delivered to storage 25 receptacles or winding devices as desired.

The preferred construction of the fulling stocks 33 and the supporting structure therefor is shown in detail in Figs. 2 and 3. Each fulling stock is 35 preferably formed from a single board or plank extending transversely of the path of travel of the cloth and from one side to the other of the machine. Each fulling stock 33 is provided with a bracket 50 near each end at the upper edge thereof, and each bracket 50 has a pin or stud 51 40 mounted therein and substantially offset with respect to the central longitudinal plane of the fulling block 33.

An endless strap or loop 52 of cotton belting 45 or other flexible material connects each pin or stud 51 to a corresponding cross pin or stud 53 (Fig. 3) mounted in the supporting bar 35 (Fig. 2) secured to the spaced lower ends of the associated forked member 37 previously described. The supporting bars 35 are preferably made from 45 channel beams, as indicated in Fig. 3.

The offset position of the pins 51 causes the fulling stocks 33 to hang in an inclined position, as shown in Fig. 2, so that when the stocks 50 descend and strike the cloth the lower ends thereof will slide in the direction of the travel of the cloth, as indicated by the arrows in Fig. 2. Each fulling stock thus has a combined rocking and sliding movement with respect to the folded 55

cloth and effectively performs a fulling operation thereon.

In Figs. 5 and 6 I have shown a slightly modified construction in which double brackets 55 are provided. With this construction the pins or studs 51 may be placed in either opening in the bracket 55, so that a fulling stock may be reversed and the wear on its lower edge may be thus distributed.

10 Bushings 56 (Fig. 6) are preferably mounted on the pins 51 and 53 to reduce the wear on the pins and to afford a surface of larger radius for the loops 52.

In Fig. 5 I have also shown the fulling stock 15 60 as provided with a detachable and replaceable lower edge portion 61. By this construction the useful life of the fulling stocks may be substantially prolonged, as all of the wear comes on the lower edge which engages the cloth.

20 In the preferred construction, as shown in Fig. 4, the top member 62 of the frame 10 is widened and recessed to provide clearance for the crank portions 38 and to provide bearings 63 for the crankshaft 40 at each side of the crankshaft portion. A firm and rigid support for the shafts 40 and for the parts associated therewith is thus provided.

I have found that the application of heat to the fulling tables 30 and 31 facilitates the fulling 30 operation, and for this reason I mount the tables 30 and 31 on guideways 70 formed at the sides of heating chambers 71 and 72. Spaced ribs 73 extend across the upper edges of the heating chambers 71 and 72 to maintain the sides thereof in fixed relation.

The chambers 72 and 73 are fixed to the left-hand side portion of the frame 10 (as viewed in Fig. 3) and are formed or provided with bracket portions 74 for additional support. The 40 heating tables 30 and 31 extend entirely across the machine and are secured to both side portions of the frame 10 by bolts 75 (Fig. 3).

An adjusting screw 76 (Fig. 3) is provided for each table 30 and 31, and each screw 76 is mounted for free rotation in a bearing 77 in the machine frame but is held from axial movement therein.

A hand wheel 78 is provided for each adjusting screw 76, and each screw 76 is threaded into a nut 80 formed at the lower end of a bracket 50 81 secured within the table 30 or 31 and depending therefrom.

The construction above described is provided so that the endless belts 20^a forming the conveyor 20 may be conveniently removed and replaced when necessary. When such replacement is desired, the bolts 75 are removed and the hand wheel 78 and adjusting screw 76 are rotated in such a direction as to withdraw the tables 30 and 31 toward the left in Fig. 3, thus providing sufficient clearance at the right-hand end of each table to permit insertion of a new belt 20^a. During such withdrawal and return movement of the fulling tables 30 and 31, these parts slide freely on the guideways 70 (Fig. 2) by which they are supported.

Each table 30 and 31 is preferably provided with a smooth covering 85 of rubber or other suitable material over which the conveyor belts slide during the fulling and washing operations. Each heating chamber 71 and 72 is provided with a plurality of steam pipes 88 (Fig. 1) by which effective heating of the tables 30 and 31 may be secured. Additional steam pipes 89 may be provided, by which heat may be applied directly to

the outer or cloth-supporting side of the conveyor belts.

An extended tank or trough 90 (Fig. 1) collects the fulling or washing solution pressed out of the cloth during a fulling or washing operation thereon, and a second and lower tank 92 may be provided to receive clear water for cleaning and flushing the conveyor belts during their idle return movement.

The upper tank 90 is supported in such manner that the conveyor belts can pass freely under the tank during their return travel. One end of the tank also clears the right-hand side portion of the frame 10 (as viewed in Fig. 3) so as to provide clearance space for removing and replacing the conveyor belts as previously described.

It is sometimes desirable to spray the cloth after it leaves the squeeze rolls 14 and to draw this moisture into or through the cloth by passing the cloth over a suction device. For this purpose I may provide a spray pipe 100 (Fig. 1) by which water may be applied to the top surface of the cloth C and I may also provide a suction tube 101 having a slotted mouthpiece 102. This suction tube is preferably mounted 25 in bearings 103 and may be turned manually from the inoperative position shown in full lines in Fig. 1 to the operative position shown in dotted lines.

Portions of rubber tube 104 are loosely mounted 30 in a frame 105 above the suction tube 101, and the cloth C is displaced upwardly against the rubber tubes 104 when the vacuum device is moved to operative position. The rubber tubes effectively close the end portions of the slot in 35 the mouthpiece 102 beyond the edges of the cloth C and thus assist in maintaining the vacuum.

The details of construction of the vacuum device and slot closing means are fully disclosed in Patent No. 2,001,417, issued to me May 14, 1935, 40 and to which reference is made for a more complete description.

The vacuum device will commonly be maintained inoperative during a fulling operation but may desirably be used during a washing operation.

A combined fulling and washing machine constructed as above described may be economically manufactured and is particularly effective for its intended purpose.

Having thus described my invention and the advantages thereof, I do not wish to be limited to the details herein disclosed, otherwise than as set forth in the claims, but what I claim is:—

1. In a fulling machine, a plurality of stocks, 55 a supporting structure therefor, and means to vertically reciprocate said structure to effect a fulling operation, said stocks being free to swing in the direction of travel of the cloth.

2. In a fulling machine, a plurality of stocks, 60 a supporting structure therefor, and means to vertically reciprocate said structure to effect a fulling operation, said stocks extending transversely of the direction of travel of the cloth and in closely parallel relation, and the lower 65 ends of said stocks being freely slideable in the direction of cloth travel.

3. In a fulling machine, a plurality of stocks, 70 a supporting structure therefor, means to vertically reciprocate said structure to effect a fulling operation, said stocks extending transversely of the direction of travel of the cloth and in closely parallel relation, and a separate flexible looped member connecting each end of each stock to said supporting structure.

4. The combination in a fulling machine as set forth in claim 3, in which said looped members are connected to each stock substantially to one side of the central longitudinal plane thereof. 5
5. A fulling machine having a plurality of fulling stocks, supporting devices therefor, and means to vertically reciprocate said devices and stocks to effect a fulling operation, each stock 10 comprising a transversely extended and freely swinging board, and said stocks being supported by said devices in closely parallel relation. 10
6. A fulling machine having a plurality of fulling stocks, supporting devices therefor, and 15 means to vertically reciprocate said devices and stocks to effect a fulling operation, each stock comprising a transversely extended and freely swinging board, and said stocks being supported by said devices in closely parallel relation and 20 each being free to swing about an offset axis at the upper edge thereof. 20
7. In a fulling machine, an inclined fulling table, means to deliver cloth in folds to said table, a plurality of fulling stocks, means to 25 operate said stocks to engage and full the cloth while on said table, a heating chamber on which said table is mounted, and means to heat said chamber, said table being longitudinally slideable on said heating chamber to provide end clearance. 30
8. In a fulling machine, an inclined fulling table, means to deliver cloth in folds to said table, a plurality of fulling stocks, means to operate said stocks to engage and full the cloth 35 while on said table, a heating chamber on which said table is mounted, said table being longitudinally slideable on said heating chamber to provide end clearance, means to slide said table, and means to heat said chamber. 40
9. In a fulling machine, means to support the cloth during a fulling operation thereon comprising an inclined fulling table, a heating chamber underlying and supporting said table, said chamber having longitudinal guideways for said 45 table, and means to move said table along said guideways. 45
10. In a fulling machine, means to support the cloth during a fulling operation thereon comprising an inclined fulling table, a heating chamber underlying and supporting said table, said chamber having longitudinal guideways for said table, means to move said table along said guideways, and means to heat said chamber. 50
11. In a fulling and washing machine, a conveyor formed of a plurality of parallel belts, a fulling table over which said belts are drawn, a drainage tank underlying said table and a 55 frame on which said table and tank are mounted within the path of travel of said belts, said table and tank being free from said frame at one end to provide clearance for belt removal and replacement. 5
12. In a fulling and washing machine, a conveyor formed of a plurality of parallel belts, a fulling table over which said belts are drawn, a drainage tank underlying said table, and a frame on which said table and tank are mounted within the path of travel of said belts, a second tank 10 underlying the lower run of said belts, and means to guide said belts through said second tank for washing thereof. 10
13. In a fulling and washing machine, fulling 15 mechanism, means to convey cloth to and from said fulling mechanism, and means to extract water from said cloth as it approaches said mechanism, said extracting means being manually and selectively movable to operative or inoperative position, said extracting means comprising a movably mounted slotted mouthpiece and portions of rubber tubing held in position to cover end portions of the slot in said mouthpiece when the latter is in operative position. 20 25
14. As an article of manufacture, a fulling stock comprising an elongated board having brackets secured thereto, each bracket having parallel spaced bearing openings disposed at opposite sides of the central longitudinal plane of 30 said board and each substantially offset therefrom, and selectively adapted to receive a supporting stud. 30
15. In a fulling machine, an inclined fulling table, means to deliver cloth in folds to said 35 table, a plurality of fulling stocks, means to operate said stocks to engage and full the cloth while on said table, said table being a chambered structure having an open bottom, a heating chamber having an open top and on which said 40 chambered table is mounted, and means to heat said chamber. 40
16. In a fulling machine having an inclined fulling table, means to deliver cloth in folds to said table, a plurality of fulling stocks and means 45 to operate said stocks to engage and full the cloth while on said table, that improvement which comprises providing a heating chamber beneath said table which is substantially trapezoidal in cross section and of which said table 50 forms the top, said chamber being effective to supply heat to said table and to said conveyor and to the cloth supported thereon during the fulling operation, and means to heat said chamber. 55

DAVID GEESNER.
